UNITED STATES PATENT OFFICE.

CHARLES H. LAWTON, OF TORRINGTON, CONNECTICUT.

MOLD FOR CASTING INGOTS.

1,197,834.

Specification of Letters Patent. Patented Sept. 12, 1916.

Application filed November 22, 1915. Serial No. 62,709.

To all whom it may concern:

Be it known that I, CHARLES H. LAWTON, a citizen of the United States, residing at Torrington, county of Litchfield, State of Connecticut, have invented an Improvement in Molds for Casting Ingots, of which the following is a specification.

This invention relates more especially to the type of molds used for casting ingots and has for its object to greatly reduce the cost of producing ingots. This reduction in cost I effect by the use of my novel molds which are made in four parts instead of two, two of the parts being permanent and two renewable. For convenience in description, I will term the renewable parts mold members and the permanent parts container members. The mold members are plain castings that match together and cost considerably less than half the cost of mold members as ordinarily constructed. In my novel structure, the foot of the mold is upon one of the container members and the drilling and other machine work for fitting the locking means is all upon the container members, which may be used continuously for an almost unlimited length of time. In two-part molds, the parts are necessarily made heavy and when the mold is worn out the clamping means is discarded with it and becomes a total loss. The mold members of my novel mold are made about one-half the weight of ordinary two-part mold members, which effects an important saving. I find furthermore that owing to the relative thinness of my novel mold members, they last very much longer than the much heavier two-part molds, thus effecting an additional saving in the cost of producing ingots. This is for the reason that when pouring takes place, the inner surface of the mold members is subjected to intense heat, which does not penetrate the mold members quickly, owing to their thickness. The result is that the mold members crack very readily, as the heat of the inner side of the members is so much greater than that of the outer side, and owing to this uneven heating alternating with cooling thereof, the mold members in addition to cracking are caused to stretch and bulge so that they deteriorate very rapidly. In my novel four-part molds,

the mold members are made relatively light and thin and the heat from the molten metal penetrates them quickly, so that the inner and outer sides of the mold members are heated more uniformly. This enables me to run a much greater number of heats without surface cracking.

In the accompanying drawings forming a part of this specification, Figure 1 is a front elevation of my novel mold complete; Fig. 2 a side elevation corresponding therewith; Fig. 3 a longitudinal section corresponding with Fig. 2; Fig. 4 a section on the line 4—4 in Fig. 1, looking in the direction of the arrows; Fig. 5 an elevation of one of the mold members; Fig. 6 an edge view as seen from the right in Fig. 5; Fig. 7 an edge view of the other mold member, and Fig. 8 is a side elevation on a reduced scale, showing the mold in operative position supported by a rack.

10 and 11 denote the mold members and 12 and 13 the container members. Mold member 10 comprises the back and bottom of the mold, and mold member 11 the sides and front of the mold, as will be readily understood from Figs. 3 and 4. The front is made slightly shorter than the back and sides, and both front and back are beveled on their inner faces for convenience in pouring. Member 10 is provided at its edges with longitudinal recesses 14 which receive the edges of the sides of the mold (part of member 11) thus closing the joints between the members. Both mold members are provided with external ribs 15, which are at the ends of the mold when assembled, and are engaged by flanges 16 on plates 17 on the container members. The mold members are castings but in comparison with ordinary mold members they are very light. The container members may be formed from stock rolled in the form of channel plates and need not be very heavy. Container member 13 has bolted thereto hinge members 19 and container member 12 has bolted thereto a central hinge member 20. A pin 21 passing through the hinge members completes the hinge, said hinge pin being secured in place by a cotter pin seated in a hole 22 in hinge member 20.

18 denotes splash guards between the

sides of the container members which protect the pins from the molten metal.

Hinge member 19 is provided with shoulders 23 upon which mold member 10 rests (see Fig. 3) and hinge member 20 is provided with a shoulder 24 on which mold member 11 rests. Pins 25 pass transversely through container members 13, and hooks 26 on said pins, which are secured thereon by cotter pins, engage similar pins 27 on container member 12 to lock the members together in use. The cotter pins in pins 25 are placed outside the hooks and the cotter pins in pins 27 are placed within the sides of container member 12. It will be noted that container member 13 is extended downward considerably below container member 12 and that hinge members 19 are likewise extended to brace and strengthen it. This extension constitutes the foot of the mold, indicated as a whole by 29, and does not have to be discarded when the mold members are worn out.

The operation of my novel four-part mold is the same as that of ordinary two-part hinged molds. The mold members are retained in place on the container members through the slidable engagement of the flanged plates on the container members with the ribs on the mold members. This construction, however, permits the mold members to be readily removed and replaced by new ones when necessary. In use, the mold is supported by a suitable rack, as in Fig. 8, and the parts are secured in place through the engagement of the hooks carried by one container member with the pins on the other container member. In removing an ingot, the hooks are disengaged from the pins, and mold member 11 and container member 12 are swung away from mold member 10 and container member 13. Mold member 11 is provided on opposite sides with recesses 28 (one only being shown) for engagement by tongs in separating the mold members to remove an ingot.

Having thus described my invention I claim:

1. A mold of the character described comprising container members formed of rolled stock, hinged together at one end, and removable mold members of cast metal having a slidable engagement with the respective container members throughout substantially the entire length of said container members.

2. A mold of the character described comprising container members formed of rolled stock movably connected at one end, and mold members of cast metal having a slidable engagement with the respective container members through substantially the entire length of said container members, the sides of said mold members and of said container members having comple-

mental devices for removably attaching the mold members to the container members.

3. A mold of the character described comprising container members formed of rolled stock movably connected at one end, mold members of cast metal having slidable engagement with the respective container members throughout substantially the entire length of said container members, and external means for removably attaching the mold members to the container members.

4. A mold of the character described comprising container members formed of rolled stock, shouldered hinge members attached thereto, complementary mold members of cast metal having slidable engagement with the respective container members throughout substantially the entire length of said container members, said mold members having their lower ends resting upon and supported by said shouldered hinge members, and means for removably connecting the mold members and the container members.

5. A mold of the character described comprising container members formed of rolled stock, one of which is provided with a downward extension, shouldered hinge members for the container members, one of said hinge members being secured to said downward extension, and having a portion bracing the same, complementary mold members of cast metal having their lower ends resting upon and supported by the shouldered portions of the hinge members, and means for removably connecting the mold members and the container members.

6. A mold of the character described comprising channel-shaped container members, flanged plates secured thereto, hinge members provided with shoulders also secured thereto, mold members supported by the shoulders and provided with ribs engaged by the flanged plates, for the purpose set forth, and means upon the container members for locking the parts in operative position.

7. A mold of the character described comprising container members, flanged plates secured thereto, hinge members provided with shoulders also secured thereto, mold members supported by the shoulders and provided with ribs engaged by the flanged plates, locking hooks upon one container member, and pins in the other container member adapted to be engaged by the hooks.

8. A mold of the character described comprising channel-shaped container members, flanged plates secured thereto, hinge members provided with shoulders also secured thereto, mold members supported by the shoulders and provided with ribs engaged by the flanged plates, pins passing through the sides of the container members and through the flanged plates, locking hooks carried by the pins on one container mem-

ber and engaging the pins on the other container member, and cotter pins for retaining the hooks and pins in place.

9. A mold of the character described comprising channel-shaped container members, each provided with a shouldered hinge member, removable mold members resting on the shoulders, locking hooks and pins

upon the respective container members, and splash guards between the sides of the container members, for protecting the locking hooks and pins. 13

In testimony whereof I affix my signature.

CHARLES H. LAWTON.
